UNITED STATES PATENT OFFICE.

JOHN STEPHENSON, OF NEW YORK, N. Y.

SIGNALING APPARATUS FOR TRAM-CARS.

SPECIFICATION forming part of Letters Patent No. 362,042, dated April 26, 1887.

Application filed January 5, 1887. Serial No. 223,460. (No model.)

To all whom it may concern:

Be it known that I, JOHN STEPHENSON, a citizen of the United States, residing in the city, county, and State of New York, have invented certain new and useful Improvements in Tram-Car-Signaling Apparatus, of which the following is a specification.

This invention concerns tram-cars operated by a conductor in addition to the driver, both of whom have functions relative to passengers, and in this instance both are concerned in the exit of passengers from the car, and the system of signals by which conductor and driver are advised of their duties.

15 In the drawings, which form a part of this specification, Figure 1 is a longitudinal section of sufficient of a tram-car to illustrate my invention. Fig. 2 is a section illustrating the arrangement and construction of one form of 20 audible signal.

In tram-cars with conductors the conductors are the responsible parties for controlling the entrance and exit of passengers, passengers being prohibited from ringing the driver's 25 signal-bell, therefore the wish of the passenger must be communicated to the conductor; but it often occurs that the passenger cannot see the conductor, nor can the conductor be always seen by the driver. Therefore my invention is a tram-car with signaling apparatus by which the driver and horses may be controlled by the sound of a bell operated by the conductor, and the conductor controlled by a different kind of sound from mechanism 30 operated by the passenger. To accomplish this object I make use of a tram-car with a driver's bell and any of the contrivances by which the conductor can operate that bell. Furthermore, and independent of the bell and 35 its operating mechanism, I attach to one or both ends of the car an audible-signal instrument, (a whistle preferred,) to which instrument is connected a cord extending along the side of the car, and on this cord I have at 40 suitable intervals pendent pulls within reach of the passengers. As more vertical motion of the pull is required to operate a whistle than to actuate a bell, I prevent excess of such motion by placing cord or strap supporting 45 sheaves at each side of the pull in close proximity thereto, so that when the pull is drawn down it brings down the two sections of the cord on opposite sides thereof, and thus takes up what would otherwise be a surplusage of 50 movement of the cord. The car with the

parts of the signaling mechanism thus exposed, it is apparent that when a passenger not seeing the conductor wishes to stop the car, the most apparent and convenient operating contrivance is the pull, and he therefore seizes, draws down the pull, and with it the cord which actuates the aforesaid sound-producing instrument. The sound instigates the conductor to ring the driver's bell, causing the driver to apply the brakes and stop 65 the car, thus accomplishing the wish of the passenger.

As stated, the audible signal may be a whistle or other contrivance for making a sound differing from that of a bell, this distinction being essential, as the horses become accustomed to the sound of a bell for starting, and, it has been found, will not distinguish between bells of different tones, so that the audible alarm must, to be practically operative, give forth an essentially different sound. In the drawings I have shown the audible alarm as a whistle, *g*, combined with a cylinder, piston, and spring for moving the piston in one direction, and with the cord *G* 70 for moving it in the other. The cord is attached to the piston at one end, to a fixed point, *x*, at the other, is provided with permanent pulls *H*, and passes over a pair of rollers or sheaves, *I*, *I*, adjacent to each pull 75 80 which hangs between them, as shown. As shown in the drawings, the usual starting-gong, *Q*, is suspended beneath the overhang of the roof and is connected with the usual belt, *R*; but any other gong-operating devices 85 90 95 may be employed.

Having thus described the means by which a passenger, though not seeing the conductor, may cause the car to be stopped, I now claim—

A tram-car provided with a bell and bell-actuating mechanism extending to the platform of the car, by which the conductor may signal to start and stop the car, and with a whistle or equivalent audible-signaling device having a sound different from a bell, and 100 connections therewith arranged within reach of the passengers in the car, whereby it may be operated by a passenger to stop the car, substantially as described.

In testimony whereof I have signed my name 105 to this specification in the presence of two subscribing witnesses.

Witnesses: JOHN STEPHENSON.

STUART A. STEPHENSON,
AUGUST RIPPERGER.
